28 Claims. (Cl. 38—22)

This invention relates to presses and more specifically to laundry presses.

In general, it is an object of the invention to provide a device of the character described which will efficiently perform the purposes for which it is intended, which is simple and economical of construction, which can be expeditiously, conveniently and safely manipulated, and which can be readily manufactured and assembled.

Another object of the invention is to provide a press which occupies a minimum of space and which does not have an excessive number of parts, and which also is so constructed that the operator may put the work onto the press at a convenient loading position and preferably at the same or substantially the same loading position for a plurality of bucks; and to provide such a press in which one head and buck may be put through a cycle of any number of operations independently, without any other head and buck being operated or while another head and buck stand in pressing engagement; and to provide such a press in which the total pressing force exerted is automatically changed in proportion to the number of bucks and heads which are in 25 pressing engagement.

Other objects of the invention will in part be obvious and will in part appear hereinafter.

The invention accordingly comprises the features of construction, combination of elements and arrangement of parts which will be exemplified in the construction hereinafter set forth and the scope of the application of which will be indicated in the claims.

For a fuller understanding of the nature and objects of the invention, reference should be had to the following detailed description, taken in connection with the accompanying drawings, in which:

Figure 1 is an end view of a machine embodying one form of the invention;

Fig. 2 is a front view of the machine shown in Fig. 1;

Figs. 3 and 4 are diagrammatic representations indicating the operation of the device shown in Figs. 1 and 2;

Fig. 5 is an end view of a machine which is a modification of the machine shown in Fig. 1;

Figs. 5a, 5b and 5c are diagrams of the operation of certain of the elements shown in Fig. 5;

Fig. 6 is a view in section looking toward one end of the device shown in Fig. 5;

Fig. 7 is a front view of the device shown in Figs. 5 and 6;

Figs. 8a and 8 are diagrammatic representa-

tions showing the operation of the machine shown in Figs. 5-7;

Fig. 9 is a front view of another form of the invention; and

Fig. 10 is a diagrammatic representation of the machine shown in Fig. 9.

The present invention contemplates a space-saving machine and a time-saving machine and one wherein each buck has its loading position 10 positioned conveniently with respect to the hands of the operator. For each buck there is a head with which that buck works. One buck and head may be pressing while another buck and head go through one or more entire cycles of loading and pressing. In this way, all parts of the machine are constantly in use and thereby pressing of various kinds can be carried on without parts of the machine standing idle. The machine may also be run so that the different 15 bucks are alternately loaded and pressed or they may be both in loading or both in pressing position. In Figs. 9 and 10, a machine is shown in which the travel of the bucks is horizontal, the bucks being at all times at about the height of the operator's hands. In Figs. 1-8a, the heads are somewhat more spaced from each other, although substantially vertically aligned, and therefore one of the bucks must move down from the work-receiving position to its head. There are practical disadvantages, e. g., loss of speed, etc., to lower that buck first and then carry it back to its head. In the machine shown in these figures, the buck is carried along a slanting path downward and backward and before reaching the end of that path it would collide with its head, which is to overlie that buck when the latter reaches its pressing position. Means are provided for avoiding this. Such means operate to remove that head from the path of its descending buck in timed relation automatically. Similarly, the head is removed from the path of its buck just before the latter starts on its slanting upward path to the work-receiving position.

In the drawings, 10 denotes a pair of spaced, vertical frames extending between and supported by which is a pair of bucks 11 and 12 and a pair of respective pressing heads 14 and 16. The material to be pressed is laid on one of the bucks while it is forwardly positioned in work-receiving position. It is then moved back into contact with its head and the material pressed between it and the head.

A shaft 18 extends between and is directly supported by the frame 10. At each end of the shaft

there is a bell crank 20 having a lower arm 22 and an upper arm 24. Buck 11 has horizontal trunnions 26 at the ends thereof and these are pivotally carried by a link 28 which is also pivotally connected to arm 24. A guide block 30 is carried by each trunnion and has a sliding motion restricted to a linear path by the guides 32. The latter extend from the neighborhood of the head 14 forwardly and downwardly toward a point which may be designated the "work-receiving" position.

Similarly, trunnions 34 at the ends of the lower buck 12 are pivoted at the ends of respective links 36, the outer ends of which are pivotally attached to the lower arms 22. Guide blocks 38 on the trunnions 34 are slidable along a linear path which leads downward and backward from the work-receiving position and which is defined by the guides 40 attached to the frame 10. The guides 32 and 40 are at an angle with each other so as to give intersecting paths for the guide blocks and bucks. The paths may intersect beyond the points where the blocks stop, at the point where the blocks stop, or the blocks may move across and beyond the point of intersection.

Means are provided to rotate the bell crank 20. These may take the form of a crank 42 pivotally attached to the arm 22 and to piston 44 which is slidable in cylinder 46 into which motivating fluid may be introduced, as described below.

There are means for moving head 16 out of the way of buck 12 as the latter is moved downward from the work-receiving position. As shown, the head 16 may be attached to arm 48 of bell crank 50 which is pivoted on frame 10. A spring 52 attached to the frame 10 and arm 54 of the bell crank 50 tends to hold bell crank 50 so that head 16 is out of the path of buck 12. There are other means for fitting head 16 over buck 12 and for pressing it against that buck after the latter has been brought down from work-receiving position. These may comprise a crank 56 pivotally attached at one end to an arm 58 of the bell crank 50 and attached at its other end to a piston 60 in cylinder 62. The arm 58 is so positioned with respect to arm 54 and spring 52 that, when fluid pressure is introduced into cylinder 62, the crank 56 forces bell crank 50 to rotate, bringing the head 16 down into pressing engagement with buck 12 when the latter is in its lower backward position.

Figs. 3 and 4 show diagrammatically the fluid-operated means and controls therefor for motivating the various parts described above. A main fluid pressure line 64 is connected to a control valve 66 which has a central element 68 rotatable in a valve casing 70. A passageway 72 in element 68 may be positioned to connect line 64 to conduit 74, which leads to cylinder 46 and also to a similar device 76, which, when fluid pressure is introduced into it, causes piston 78 to push head 14 down upon buck 11 against the action of springs 80 which normally keep head 14 spaced from buck 11. The pressure in cylinder 46 causes crank 42 to move out of the cylinder, forcing arm 22 upward until buck 12 is in work-receiving position. Just as arm 22 and arm 24 reach the highest point of their travel, arm 22 contacts valve means 82 in the fluid pressure line leading to cylinder 76. By this means, head 14 is not pushed down until buck 11 is in position to receive it. Beyond the valve 82, in the branch of line 74 which goes to the cylinder 76, there is an offshoot leading to a cylinder 84 from which a piston rod 86 extends as a tongue. That tongue is normally held retracted by spring 88 but, when the pres-

sure is allowed to pass valve 82, it enters cylinder 84, forcing tongue 86 against a lower side of guide block 30 and prevents the buck 11 from being pushed out of position by the head 14, as the latter presses against buck 11.

While the pressure has been causing the parts to move as described, a channel 90 in valve element 68 is connected to valve vent 92 with pressure conduit 94 which leads to cylinder 62 through a pressure control device 96. With no pressure in cylinder 62, spring 52 causes bell crank 50 to rotate so as to lift head 16 out of the path of buck 12 so that the latter may move upward due to the force on arm 22. As will be seen later, the motion of head 16 out of the path of buck 12 takes place before the latter begins its upward and forward motion.

When it is desired that the upper buck 11 shall be brought to work-receiving position and the lower buck 12 be carried back down to pressing position, valve element 68 is rotated counterclockwise, as shown in Figs. 3 and 4, by any suitable means such as handle 98. Valve element 68 first reaches a position such that passageway 72 no longer connects the main pressure line 64 and line 74, but does connect vent 92 and line 74. This causes loss of pressure in cylinders 76, 84 and 46 whereby, respectively, head 14 is raised from buck 11 by springs 80, tongue 86 is withdrawn from the path of guide blocks 30 by spring 88 and the upward pressure on arm 22 is no longer exerted by crank 42. In this fashion, the main bell crank is left free to rotate clockwise, under the action of gravity, from the position shown in Fig. 1. The rotation of the bell crank 20 is prevented from being too rapid by having a pressure control device 104 in the portion of line 74 which leads to cylinder 46. In this way, cylinder 46 acts as a dash-pot.

A further motion of valve element 68 brings passageway 72 into a position to connect the main pressure line 64 and line 94 leading to cylinder 62. However, since head 16 cannot press onto buck 12 until the latter is in its completely retracted position, the pressure control device or shut-off valve 96 is provided in line 94. Valve 96 is opened by arm 22 when the latter reaches its lowermost position. Buck 12 is then in retracted position. The pressure passes through valve 96 into cylinder 62, moving crank 56 outward and thereby rotating bell crank 50 so as to bring head 16 down against buck 12 with as much force as is desired.

To bring the machine back into the position shown in Fig. 3, the valve 66 is turned back from the position shown in Fig. 4 to the position shown in Fig. 3. This causes the loss of pressure from cylinder 62, the latter being connected to vent 92. Spring 52 then acts to raise head 16 and pressure is admitted to cylinder 46 whereby the entire process for the turning of the main bell crank 20 is begun again. The pressure control element 104 in line 74 delays the setting-up of pressure in cylinder 46 and, hence, the raising of arm 22 by a length of time sufficient to permit spring 52 to raise head 16 out of the path of arm 22.

The machine shown in Figs. 5-7 is similar to that shown in Figs. 1 and 2 except that arms 22 and 24 are separately rotatable about shaft 18 as an axis and means are provided for bringing either of the bucks into work-receiving position independently of the other buck. Thus, both bucks may be withdrawn and in pressure relation with their specific heads at the same time.

Means are provided for assuring that one buck

is held at its pressure position whenever the machine is operated to bring the other buck to the work-receiving position. As shown, these means comprise a toggle mechanism. There is a guide 108 fixed to each frame 10. Each guide provides a vertical linear path for a guide block 108 to which is connected a push rod 110 at the lower end of which is a plunger 112 which operates in cylinder 114. Attached to the guide block 108 is a shaft 116 on which pivot toggle 118, the latter extending in opposite directions from the shaft 116. A link 120 is pivotally connected to one end of toggle 118 and to the upper arm 24. Another link 122 is pivotally joined to the other end of the toggle and to the lower arm 22.

The operation of the toggle, the toggle links 120 and 122, the crank arms 24 and 22, with the bucks 11 and 12 attached respectively to the latter arms, is shown diagrammatically in Figs. 5a, 5b and 5c. In Fig. 5a, the diagram represents the device as shown in Fig. 5 with each buck in pressing position, the upper buck being in upper position and the lower buck being in lower position. Fig. 5b shows what occurs when shaft 116, at the center of the toggle 118, is moved upward from the position shown in Fig. 5a, by means to be described below. Since arm 24 is raised as far as it can go, the raising of shaft 116 causes link 120 to pivot around its attachment to arm 24 without the latter being moved. At the same time as shaft 116 rises, toggle 118 pivots clockwise around the free end of link 120. The other end of toggle 118 moves upward in an arc clockwise around the free end of link 120. This causes link 122 to be raised upward, forcing arm 22 up until buck 12 on arm 22 is raised to its upper forward work-receiving position. The reverse action brings buck 12 back to the position shown in Figs. 5 and 5a.

Instead of moving buck 12 to work-receiving position, it may be desired to leave it in its lower pressing position and to bring buck 11 forward and downward to the work-receiving position. To do this, shaft 116 is moved downward by means described below. In this case, since bell crank arm 22 is as far down as it can go, the end of link 122, which is attached to arm 22, remains fixed. As shaft 116 is lowered, link 122 rotates clockwise about its point of support on arm 22. Toggle 118 rotates clockwise about the freely moving end of link 122 and about shaft 116. This causes the end of toggle 118, which is attached to link 120, to move arcuately downward, pulling arm 24 and buck 11 down until the latter reaches work-receiving position (see Fig. 5c). These last-described means may be reversed by raising shaft 116 until buck 11 is again in its upper pressing position.

Figs. 8a and 8 show diagrammatically the fluid pressure means and controls for operating the toggle means and the head which are to be compressed against the bucks. Fig. 8a shows central toggle shaft 116 at the mid-point of its vertical motion. With the shaft in that position, arm 24 is raised and arm 22, as described above, is lowered. Each buck is in position to receive its pressing head. The shaft 116 has been brought to its mid-position by connecting the main fluid pressure line 64 through valve 810, by suitable manipulation thereof, to line 874 which leads to cylinder 114. By controlling the amount of pressure by means of valve 810, plunger 112 and push-rod or crank 110 may be caused to hold shaft 116 at the mid-point of its travel. After

shaft 116 has been so placed, the pressure in line 64 may be caused to enter line 875 through valve 811. A valve 813 in line 875 is only opened when arm 24 reaches its upper position and contacts an element of 813, whereupon the pressure in line 875 is transmitted further therealong until it reaches cylinder 116 and operates the head 114 to compress it against buck 11. Simultaneously, the pressure also passes along to chamber 84 which operates tongue 86 to lock buck 11 in place, as described in connection with the device shown in Fig. 1.

Either before or after head 114 has been pressed against buck 11 but, in any event, after shaft 116 has been brought to its mid-point, the pressure in line 64 may be admitted to line 877 through valve 811 whereby the pressure is introduced into cylinder 815, moving the piston therein which, in turn, moves the crank 817 the outer end of which is pivotally attached to an arm 819 which is pivoted at 821 and to which is fixed head 116. The head 116 is normally kept by gravity out of the path of buck 12. The operation of crank 817 pivots arm 819 to bring head 116 in line with the lowered buck 12. The pressure in line 877 is also transmitted to a cylinder 822 having a piston 823 which presses against the buck 12 in its lower position and presses it against its head 116. The pressure in line 877 does not reach cylinders 815 and 822 until arm 22 has reached its lower position and contacted an element of valve 88 which shuts off those cylinders from line 877 until so operated.

When it is desired to lower the upper buck 11 to work-receiving position, valve 811 is operated so to connect line 875 through a passage 825 to vent 827. This causes the tongue 86 to be retracted and causes head 114 to cease to be pressed against buck 11. Then valve 810 is manipulated so as to cause some of the pressure in line 874 to be lost through vent 829. Thereby, the crank 110 retracts shaft 116, causing link 120 and arm 24 to be pushed downward until head 11 reaches work-receiving position.

When it is desired to leave buck 11 in pressing position and to bring buck 12 to work-receiving position, line 877 is vented through valve 811. Thereupon, buck 12 is brought out of pressure contact with head 116 and the latter is swung away out of the path of buck 12. Next, valve 810 is operated to permit more pressure to pass through line 874 into cylinder 114 whereby push-rod 110 raises guide block 108 upward, which motion is transmitted to toggle 118, link 122 and arm 22. The latter, in being raised, carries buck 12 with it upward and forward to work-receiving position—the parts then being as shown in Fig. 8. By reducing the pressure in 114 and introducing pressure again into line 877, the machine may be brought to the arrangement shown in Fig. 8a.

For purposes of clarity, the valve arrangements have been shown in Figs. 8a and 8 as though they were in two separate valves. In practice, these may be combined in a single valve, so arranged that a single continued motion thereof successively causes the machine to assume its various positions.

In Figs. 9 and 10 there is shown another form of the machine in which the pressing heads may be simultaneously pressed against their respective bucks but which may be so operated that, if desired, a single head presses upon a single buck only. The heads are substantially fixed, having but a slight straight up and down motion just suf-

ficient to allow horizontal motion of the bucks without disturbing the garments which lie on the bucks. The simultaneously movable bucks travel on spaced horizontal ways which lead to forward receiving positions quite in front of the head. The bucks may be moved forward together or backward together, or one may be moved forward while the other is being moved backward, or one may be moved backward and forward as much as desired while the other is kept in pressing position, or while the other is kept in forward position.

In Figs. 9 and 10, 901 denote a pair of frame uprights connected by an overhead element 903. Each upright carries horizontal guide or track elements 904a and 904b which are vertically spaced from each other. Springs 905 support an upper pressing head 916b from frame element 903. Lower pressing head 916a is connected to the upper head by elements extending from each end of each head to the same end of the other head and comprising, for example, a pair of telescoping tubes 907. The latter are intersupported by pins 909. When desired, the pins may be removed, leaving the lower head 916a resting on its buck 912a. The latter is then out of operation while the upper head 916b continues to cooperate with its buck 912b. In pressing position, each buck is directly beneath its head.

Pneumatic means are provided to cause the various motions of the heads and bucks. A main conduit 918 acts as a source of fluid pressure. A valve 920a controls that pressure in its relation to the lower buck 912a and the corresponding lower head 916a. A conduit 922a connects valve 920a with a cylinder 924a from which there movably extends a telescoping piston rod 926a which is attached to the frame of the lower buck 912a. A spring 928a, attached to the frame of buck 912a and upright 901, tends to hold that buck in pressing position where it remains unless pushed forward by piston rod 926a. Other means, such as weights, etc., may be substituted for the spring.

The valve 920a is connected through conduit 930a to chamber 932a which may be supported by frame element 903 and in which there is a piston 934a. A piston rod 936 leads from the piston out of chamber 932a and is attached to the upper head 916b which, as described above, is connected to lower head 916a by telescoping tubes 907. A return conduit 938a leads from chamber 932a to valve 920a and is used, as described hereafter, to remove the pressure from chamber 932a. A check valve 940a in this conduit prevents the passage of fluid except in a direction away from chamber 932a. A vent 942a leads from valve 920a to the atmosphere.

A similar valve 920b and a set of similar conduits (shown on the drawings with suffix b) control the fluid pressure which operates the upper head 916b. The piston rod 936b leads from the piston 934b into chamber 932b and is attached to piston 934a. The motion of the piston 934b is thus communicated directly to the upper head 916b through the intermediate elements 934a and 936.

The travel of the heads is straight up and down but need only be sufficient to permit the bucks, and the material which is to be or has been pressed, to move to and away from the pressing position without the disturbing of that material. Bucks and heads are sometimes somewhat curved. The motion of the heads is sufficient to allow the bucks to move horizontally away from the heads in spite of that curvature. The motion of the

heads need be, under some circumstances, so slight that the heads may be considered substantially fixed. The forward motion of the bucks is sufficient to expose their work-supporting surfaces so that an operator has no difficulty in properly arranging the material thereon which is to be pressed.

The structure of the valves 920a and 920b will next be described in connection with the operation of the machine. Assume that the lower buck is back in pressing position as shown and that it is desired to move the upper buck back to pressing position. The handle 944b of the valve 920b is moved from its neutral position at which it is nor-

10 mally held by means such as springs, not shown, to the position marked "In." In the neutral position "N," there is no connection between pipe 918 and pipe 922b and a valve element 946b covers the vent 942b which would otherwise be connected

15 by passage 948b to the return conduit 938b from the pressing head cylinder. In the neutral position, however, the fluid pressure supply line 918 is connected to the conduit 930b which carries pressure to the chamber 932b so that both press-

20 ing heads are down in pressing position. As the valve handle is moved to the "in" position, the element 946b moves away from and uncovers vent 942b so that the latter is connected, by means of

25 passageway 948b, to the pressing head chamber vent line 938b and, at the same time, the vent 942b is also connected by that passageway to the line 922b which supplies pressure to the buck piston. These pressures having been vented, the

30 springs 905 raise the heads 916a and 916b and the spring 928b is free to draw back the buck 912b along upper tracks 904b to pressing position under its head. When the valve is in "in" position, the

35 conduit 930b is shut off. Valves 950a and 950b are provided in the lines 930a and 930b, respec-

40 tively. There is a connecting linkage between valve 920b and 950a and between 920a and 950b. The motion of the valve 920b to "in" position causes, through the linkage, the valve 950a to close. This prevents the pressure from line 918

45 passing through pipe 930a from being vented through 938a and 938b which open into each other at the connection 952 and hence out through vent 942b.

The handle of valve 920b is then released and 50 it automatically returns to neutral position whereby pressure is supplied from line 918 to the chamber 932b, causing the heads to return to pressing position again. The motion back to neutral position also permits valve 950a to be reopened 55 so that pressure is transmitted against piston 934a as well as against 934b. As the valve returns to neutral position, no pressure is admitted to the buck piston cylinder 924b. In order to insure that head 916b does not come out into pressing 60 position until buck 912b is completely back in pressing position, there is a valve 952b in the pressure line to the cylinder 932b which valve is only opened by the contact therewith of a finger 954b on the buck 912b. This finger can only operate 65 the said valve when the buck has reached its pressing position. The lower buck 912a likewise is provided with a finger 954a cooperating with valve 952a.

The foregoing has described the operation of 70 the machine when the upper buck is moved from work-receiving to pressing position while the lower buck is in pressing position. That motion would take place in the same manner if the lower buck had been in forward position during the same

time. Either buck may be moved in this fashion while the other is either forward or backward. A simultaneous manipulation of the valves, by a common element for example, causes both bucks to be moved together to pressing position.

When both bucks are in back position with a head pressing respectively against each, the operation of parts to bring either buck forward to work-receiving position while the other buck remains back in engagement with its head is as follows. Assume buck 912b is to be brought forward to the position shown in Fig. 10. Valve 920b is turned to "out" position. (1) This motion shuts off conduit 930b from fluid pressure supply line 918. (2) It operates valve 950a and shuts off conduit 930a from fluid pressure supply line 918. (3) It uncovers the vent 942b which thereby opens into passageway 948b. This vents cylinder 932b through conduit 938b and cylinder 932a through conduit 938a which is always connected with conduit 938b at point 952. Springs 905 then lift both heads off the bucks. (4) It connects line 918 through conduit 922b to the upper buck cylinder 924b whereby pressure entering therein pushes out the piston rod 926b. Buck 912b is thereby pushed forward on upper guide tracks 904b to work-receiving position.

The valve 920b is then allowed to snap back to neutral. Thereupon, (1) element 948b covers vent 942b, permitting pressure to be built up again in the head cylinders if and when it is reintroduced there; (2) pressure is reintroduced from source 918 into conduit 930b as far only as valve 952b; (3) valve 950a is returned to open position, introducing pressure again into conduit 930a and head cylinder 932a. This causes both heads to lower to pressing position but with only half as much total force as when pressure was in both head cylinders 932a and 932b and when each head was against its buck.

By a similar motion of valve 920a instead of valve 920b, buck 912a may be brought forward instead of buck 912b or by a simultaneous motion of the valves, both bucks may be brought forward simultaneously.

It is intended that both tracks 904a and 904b should be not far from each other and that the front ends of both should be at a position convenient for loading by an operator. Should the lower tracks be too low for convenient loading, means may be provided (pistons, linkages, etc.) for raising the lower buck when it reaches the front end of the lower tracks. Or, should the upper tracks be too high for convenient loading, similar means may be provided for lowering the upper buck when it reaches the front end of the upper tracks.

The parts of the machine shown in Figs. 9 and 10 have been described as operating so that the heads are down in pressing position while the bucks are in work-receiving position so that the heads have to be raised slightly when the bucks move to pressing position. The parts may, however, be arranged so that the heads are in raised position while the bucks are in work-receiving position. Also, each head may be on its own separate piston and each head may, if desired, come down wholly independently of the other and/or move with the other head.

It is often advantageous to have a part of the press in pressing operation for a long period while another part performs successive, shorter pressing acts. Thus, one part of a garment may be heavier and need a longer pressing, or it may need a more complete press. During such a pressing, the oper-

ator is free to press various smaller parts of another similar garment. The machine described above permits this to be done. Neither the buck nor the operator needs to be idle because the other buck has not finished its pressing in any particular case.

Since certain changes may be made in the above construction and different embodiments of the invention could be made without departing from the scope thereof, it is intended that all matter contained in the above description or shown in the accompanying drawings shall be interpreted as illustrative and not in a limiting sense.

It is also to be understood that the following claims are intended to cover all the generic and specific features of the invention herein described and all statements of the scope of the invention which, as a matter of language, might be said to fall therebetween.

Having described my invention, what I claim as new and desire to secure by Letters Patent is:

1. In a device of the character described, the combination comprising a first head, a second head which is at all times higher than said first head, a first buck associated only with said first head, a second buck associated only with said second head, means for moving said first buck from a pressing position beneath said first head to a forward work-receiving position which position is in a vertical plane spaced from said heads and between said heads and the operating station of the operator of said buck and which position is sufficiently forward of said first head to expose the entire work-receiving surface of said first buck independently of the position of said first head, means for moving said second buck from a pressing position beneath said second head to a work-receiving position which is sufficiently forward of said second head to expose the entire work-receiving surface of said second buck independently of the position of said second head, and means for moving said heads and their respective bucks into pressing engagement simultaneously, said means for moving including means for giving a relative motion, between each of said heads and all of said bucks.

2. In a device of the character described, the combination comprising a first head, a second head which is at all times higher than said first head, a first buck associated only with said first head, a second buck associated only with said second head, means for holding said first buck in a pressing position beneath said first head, means for holding said first buck in a forward work-receiving position which position is in a vertical plane spaced from said heads and between said head and the operating station of the operator of said buck and which position is sufficiently forward of said first head to expose the entire work-receiving surface of said first buck independently of the position of the first head, means providing a path between said positions and means for moving said first buck along said path between said positions, means for moving said second buck from a pressing position beneath said second head to a work-receiving position which is sufficiently forward of said second head to expose the entire work-receiving surface of said second buck independently of the position of said second head, and means for moving said heads and their respective bucks into pressing engagement simultaneously.

3. In a device of the character described, the combination comprising a plurality of bucks for and positioned for carrying articles to be pressed,

a plurality of heads permanently in substantially vertical alignment one above another, each of said heads being permanently and only associated with one of said bucks, and means for simultaneously moving a plurality of said heads and a plurality of said bucks into pressing engagement in pairs.

4. In a device of the character described, the combination comprising a plurality of bucks, a plurality of heads permanently in substantially vertical alignment one above the other, each of said heads being permanently and only associated with one of said bucks, and means for simultaneously moving a plurality of said heads and a plurality of said bucks into pressing engagement in pairs, and means for giving a relative motion between each of said heads and all of said bucks.

5. In a device of the character described, the combination comprising a plurality of bucks for and positioned for carrying articles to be pressed, a plurality of heads permanently in substantially vertical alignment one above another, each of said heads being permanently and only associated with one of said bucks, and means for simultaneously moving each of said bucks from pressing to work-receiving position.

6. In a device of the character described, the combination comprising a plurality of bucks for and positioned for carrying articles to be pressed, a plurality of heads permanently in substantially vertical alignment one above another, each of said heads being permanently and only associated with one of said bucks, and means for simultaneously moving each of said bucks from work-receiving to pressing position.

7. In a device of the character described, the combination comprising a plurality of substantially fixed heads permanently in substantially vertical alignment, a plurality of bucks, each of said heads being permanently and only associated with one of said bucks, means to move each buck horizontally back and forth between a rearward position directly beneath its head and a work-receiving position forward of its head by an amount such that the entire work-receiving surface of said buck is exposed to receive work thereon, means for bringing the respective pairs of said heads and said bucks at one time into pressing engagement by a substantially linear vertical motion, and means for linearly and vertically separating simultaneously each respective head and buck by an amount such that said bucks may be moved, with garments thereon, between said rearward and said forward position.

8. In a device of the character described, the combination comprising a plurality of substantially fixed heads permanently in substantially vertical alignment, a plurality of bucks, each of said heads being permanently and only associated with one of said bucks, means to move each buck horizontally and separately back and forth between a rearward position directly beneath its head and a work-receiving position forward of its head by an amount such that the entire work-receiving surface of said buck is exposed to receive work thereon, means for bringing the respective pairs of said heads and said bucks at one time into pressing engagement by a substantially linear vertical motion, and means for linearly and vertically separating simultaneously each respective head and buck by an amount such that said bucks may be moved, with garments thereon, between said rearward and said forward position.

9. In a device of the character described, the combination comprising a plurality of substantially fixed heads permanently in substantially vertical alignment, a plurality of bucks, each of said heads being permanently and only associated with one of said bucks, means to move each buck horizontally and separately back and forth between a rearward position directly beneath its head and a work-receiving position forward of its head by an amount such that the entire work-receiving surface of said buck is exposed to receive work thereon, means for bringing the respective pairs of said heads and said bucks at one time into pressing engagement by a substantially linear vertical motion, means for linearly and vertically separating simultaneously each respective head and buck by an amount such that said bucks may be moved, with garments thereon, between said rearward and said forward position, and means for causing one of said heads to become inoperative.

10. In a device of the character described, the combination comprising a plurality of substantially fixed heads permanently in substantially vertical alignment, a plurality of bucks, each of said heads being permanently and only associated with one of said bucks, means to move each buck horizontally and simultaneously back and forth between a rearward position directly beneath its head and a work-receiving position forward of its head by an amount such that the entire work-receiving surface of said buck is exposed to receive work thereon, means for bringing the respective pairs of said heads and said bucks at one time into pressing engagement by a substantially linear vertical motion, and means for linearly and vertically separating simultaneously each respective head and buck by an amount such that said bucks may be moved, with garments thereon, between said rearward and said forward position.

11. In a device of the character described, the combination comprising a plurality of heads, a plurality of bucks, means for moving only any predetermined one of said bucks between a work-receiving and a pressing position, and means for moving respective ones of said heads and said bucks simultaneously, as a plurality of pairs, into pressing engagement.

12. In a device of the character described, the combination comprising a plurality of heads permanently in substantially vertical alignment one above another, a plurality of bucks, means for moving said bucks between a forward work-receiving position which is in a vertical plane spaced from said heads and between said heads and the operating station of the operator of said device and a rearward pressing position, and means for moving respective ones of said heads and said bucks simultaneously into pressing engagement.

13. In a device of the character described, the combination comprising a plurality of heads permanently in substantially vertical alignment one above another, a plurality of bucks for and positioned for carrying articles to be pressed, means for moving said bucks horizontally to a work-receiving and to a pressing position, and means for moving a plurality of said heads and a plurality of said bucks simultaneously in pairs into pressing engagement.

14. In a device of the character described, the combination comprising a plurality of heads, a plurality of bucks, means for moving said bucks between a work-receiving and a pressing posi-

tion, means for moving a plurality of said heads and a plurality of said bucks simultaneously in pairs into pressing engagement, and means for moving said heads out of pressing positions when one of said bucks is moved to pressing position.

15. In a device of the character described, the combination comprising a plurality of heads, a plurality of bucks for and positioned for carrying articles to be pressed, means for moving said bucks between a work-receiving and a pressing position, means for moving a plurality of said heads and a plurality of said bucks simultaneously in pairs into pressing engagement, and means successively for moving said heads out of pressing positions when one of said bucks is moved to pressing position and the other buck is in pressing position and for moving said heads into said pressing positions when one buck is in pressing position.

16. In a device of the character described, the combination comprising a plurality of bucks, a plurality of heads, means for simultaneously moving in pairs, a plurality of said heads and a plurality of said bucks into pressing engagement, and means for applying a total pressing force to said heads in proportion to the number of bucks in pressing position.

17. In a device of the character described, the combination comprising a plurality of bucks, a plurality of heads, means for simultaneously moving respective ones of said heads and said bucks into pressing engagement, and means for automatically applying a total pressing force to said heads in proportion to the number of bucks in pressing position.

18. In a device of the character described, the combination comprising a plurality of heads, a plurality of bucks for and positioned for carrying articles to be pressed, means for moving said bucks between a work-receiving and a pressing position, means for moving respective ones of said heads and said bucks simultaneously into pressing engagement, and means automatically for moving said heads out of pressing position when one of said bucks is about to be moved from pressing position and means for moving only one of said bucks from pressing position.

19. In a device of the character described, the combination comprising a plurality of heads, a plurality of bucks for and positioned for carrying articles to be pressed, means for moving said bucks between a work-receiving and a pressing position, means for moving respective ones of said heads and said bucks simultaneously into pressing engagement, and means successively and automatically for moving said heads out of pressing position when one of said bucks is about to be moved from pressing position and for moving said one away from pressing position and means for moving only one of said bucks from pressing position.

20. In a device of the character described, the combination comprising a plurality of heads, a plurality of bucks, means for moving one of said bucks to pressing position from work-receiving position, means for moving another of said bucks to pressing position from work-receiving position while the first-mentioned one of said bucks is in said work-receiving position, means for moving said heads and said bucks simultaneously into pressing engagement after the first-mentioned buck has moved to its pressing position and again after the second-mentioned buck has moved

5 to its pressing position, and means for moving said bucks simultaneously and automatically out of their said pressing positions before the second-mentioned buck is moved to its pressing position.

21. In a device of the character described, the combination comprising a plurality of heads, a plurality of bucks, means for moving one of said bucks from pressing position to work-receiving position, means for moving another of said bucks from pressing position to work-receiving position while the first-mentioned one of said bucks is in work-receiving position, means for moving said heads and said bucks simultaneously out of pressing engagement before the first-mentioned buck starts to move from its pressing position, and means for returning said heads to said pressing positions after the first-mentioned buck has moved from its pressing position.

22. In a device of the character described, the combination comprising a buck and a head, a second buck and a second head, means for moving said bucks along paths from substantially the same work-receiving position toward their respective heads, said paths being at an angle with each other, and means for temporarily preventing at least one of said bucks from reversing its respective motion.

23. In a device of the character described, the combination comprising a buck and a head, a second buck and a second head, means for successively moving said bucks along paths from substantially the same work-receiving position toward their respective heads, said paths being at an angle with each other, means for temporarily preventing at least one of said bucks from reversing its respective motion, and means operative thereafter for compressing the respective bucks and heads.

24. In a device of the character described, the combination comprising a movable buck and a head, a second movable buck and a second head, means for moving one of said bucks along a path between its head and a work-receiving position, and for simultaneously and automatically holding the other of said bucks in substantially fixed position.

25. In a device of the character described, the combination comprising a movable buck and a head, a second movable buck and a second head, means for moving one of said bucks along a path between its head and a work-receiving position and for simultaneously and automatically holding the other of said bucks in substantially fixed position, said means comprising toggle elements.

26. In a device of the character described, the combination comprising a movable buck and a head, a second movable buck and a second head, means for moving one of said bucks along a path between its head and a work-receiving position and for simultaneously and automatically holding the other of said bucks in substantially fixed position, said means comprising toggle elements, and fluid-operated means for controlling said elements.

27. In a device of the character described, the combination comprising a plurality of bucks, a plurality of heads, means for moving said bucks into substantially the same work-receiving position, means for moving said bucks respectively into positions adjacent said heads, and means for simultaneously compressing each of said bucks against respective ones of said heads.

28. In a device of the character described, the

combination comprising a buck and a head, a second buck and a second head, toggle means for moving one of said bucks from work-receiving position to a position adjacent one of said heads and for moving the other of said bucks from a position adjacent the other of said heads substantially to said work-receiving position, and mov-

able means for operating, upon a predetermined displacement of said movable means, said toggle means to so move said one of said bucks and for operating, upon a further similar displacement of said movable means, said toggle means to so move said other of said bucks.

LEO M. KAHN.
